UNITED STATES PATENT OFFICE

FRANK JOHN ANDERSON, OF FORT DODGE, IOWA

CROSS-ARM WIRE CLAMP

Application filed January 20, 1930. Serial No. 422,063.

The object of my invention is to provide a cross arm wire clamp which is simple, durable and comparatively inexpensive to manufacture.

More particularly it is my object to provide a cross arm wire clamp comprising a body member adapted to be secured to a cross arm and clamp means on the body member to retain a pair of wires extending in opposite directions from the cross arm, means being provided on the body member to receive an end of a wire pulling mechanism such as a block and tackle or a wire stretcher whereby a wire may be pulled taut by such mechanism and then retained relative to the wire clamp in taut position for splicing or attaching to an insulator on the cross arm.

Another object is to provide a wire clamp adapted to be secured to the cross arm on an electric or telephone pole, and consisting of a two part member, the parts of which are hinged together, means being provided for clamping them around the cross arm.

A further object is to provide a wire clamp with retaining means whereby wires may be clamped and easily spliced adjacent a cross arm by a lineman seated on the arm without reaching way out to the end of the tackle block or wire stretcher when splicing wires together.

Another object is to provide a toggle lever and link means for clamping the two parts of the wire clamp together around a cross arm.

With these and other objects in view my invention consists in the construction, arrangement and combination of the various parts of my device, whereby the objects contemplated are attained as hereinafter more fully set forth, pointed out in my claims, and illustrated in the accompanying drawings in which:

Figure 1 is a perspective view of my cross arm wire clamp.

Figure 2 is a side elevation of the same illustrating it clamped around a cross arm on a pole and showing a block and tackle connected with the cross arm wire clamp for pulling a wire taut.

Figure 3 is an end elevation of the wire

clamp as viewed from the right hand side of Figure 2.

Figure 4 is a cross sectional view on the line 4-4 of Figure 1.

On the accompanying drawings I have used the reference character 10 to indicate an electric, telephone, or other type of pole to which a cross arm 12 is secured. An insulator 14 is illustrated in mounted position on the cross arm 12.

My cross arm wire clamp is referred to generally by the reference character A and comprises a U shaped portion 16 and a handle portion 18 hinged thereto by a hinge connection 20. The U shaped portion 16 is adapted to fit under the cross arm 12, and the handle portion 18 is provided with an upward bulge 22 adapted to fit over the top of the cross arm 12.

The handle portion 18 is adapted to be clamped to the U shaped portion 16 by a toggle lever 24 and link 26. One end of the link 26 is pivoted to the toggle lever and the other is pivoted to a lug 28 on the under side of the handle 18. The upper end of the toggle lever 24 is adapted to coact with a hook portion 30 on the U shaped member 16 as best shown in Figure 2 of the drawings. The toggle lever is held in the position illustrated due to the link 26 passing over center with respect to the pivotal engagement between the upper end of the toggle lever and the link 30 when the toggle lever is moved to clamped position.

Wire retaining means is provided on the top of the handle portion 18 and consists of a wedge retainer 32 secured to the handle portion 18. The shape of the wedge container is best illustrated in Figure 4 of the drawings. A pair of wedge members 34 is mounted in the wedge retainer 32 and are oppositely inclined. Projections 36 on the small ends of the wedges prevent their removal from the wedge retainer 32. The under surfaces of the wedges 34 are preferably corrugated or serrated. Beneath the wedges 34 the top of the handle portion 18 may be built up as indicated at 38.

An eye 40 is formed on the U shaped portion 16 of the cross arm wire clamp A and an

eye 42 is formed in the outer end of the handle portion 18 as clearly illustrated in Figure 1. The eyes 40 and 42 are adapted to receive one end of a wire pulling mechanism 44 which may be either a block and tackle structure or a wire stretcher. The other end of the wire pulling mechanism 44 is adapted to be clamped to the wire 46 as illustrated for instance in Fig. 2 so that such wire can be pulled taut and then clamped by one of the wedges 34. The wire pulling mechanism 34 can then be shifted to the other eye and a second wire 48 pulled taut and clamped. The wires 46 and 48 can now be easily spliced adjacent the cross arm 12 by a line-man sitting on the cross arm.

The wire pulling mechanism can also be used for pulling a wire taut which is to be secured to the insulator 14. Instead of using a wire pulling mechanism the wire can be extended between the portions 38 and 34 and down to the ground from where it can be pulled taut by the line-man and when released the wedge will tighten on the wire and clamp it relative to the cross arm wire clamp.

Some changes may be made in the construction and arrangement of the parts of my device without departing from the real spirit and purpose of my invention, and it is my intention to cover by my claims, any modified forms of structure or use of mechanical equivalents, which may be reasonably included within their scope.

I claim as my invention:

1. A cross arm wire clamp comprising a body member adapted to be secured to a cross arm, means on said body member to receive one end of a wire pulling mechanism and clamp means on said body member to retain a wire after being pulled taut by said mechanism.

2. A cross arm wire clamp comprising a two part body member, toggle lever and link means for clamping the two parts of said member together around a cross arm and clamp means on one of said parts to receive and retain a wire.

3. A cross arm wire clamp comprising a two part body member, means on one of said parts to receive one end of a wire pulling mechanism, means for clamping the two parts of said member together around a cross arm and clamp means on one of said parts to receive and retain a wire after being pulled taut by said mechanism.

4. A cross arm wire clamp comprising a two part body member, means on one of said parts to receive one end of a wire pulling mechanism, means for clamping the two parts of said member together around a cross arm and clamp means on one of said parts to receive and retain a pair of wires extending in opposite directions from said cross arms after said wires have been drawn taut by said mechanism.

5. A cross arm wire clamp comprising a body formed of a U shaped member and a handle lever hinged thereto, means for clamping said U shaped member and said lever together around the cross arm, means on said body to receive and retain a wire and means on said U shaped member and on said handle lever for connecting a wire pulling mechanism to said cross arm wire clamp.

Des Moines, Iowa, December, 1929.

FRANK JOHN ANDERSON.
